ALBERT BROADMEYER, OF HARRISBURG, PENNSYLVANIA, ASSIGNOR TO THE W. O. HICKOK MANUFACTURING CO., OF HARRISBURG, PENNSYLVANIA, A CORPORATION OF PENNSYLVANIA.

TABLE-ADJUSTING MECHANISM FOR PAPER-FEEDING MACHINES.

1,183,629.

Specification of Letters Patent.

Patented May 16, 1916.

Original application filed May 20, 1915, Serial No. 29,326. Divided and this application filed August 5, 1915. Serial No. 43,783.

To all whom it may concern:

Be it known that I, ALBERT BROADMEYER, a subject of the Emperor of Germany, and a resident of Harrisburg, in the county of 5 Dauphin and State of Pennsylvania, have invented certain new and useful Improvements in Table-Adjusting Mechanism for Paper-Feeding Machines, of which the following is a specification.

10 My present invention relates generally to paper feeding machines of that nature described and shown in my application Number 29,326, filed May 20, 1915, and is, more particularly an improved mechanism and 15 means for adjusting the paper holding table thereof as the paper is fed from the table, this application being a division of my application Number 29,326, just mentioned.

The primary object of my present invention is to provide a table adjusting mechanism which will operate with equal facility, accuracy, and general effectiveness in connection with rough, smooth, thick, or thin paper, and to do this automatically, imparting a step by step upward movement to the table in order to maintain its paper stack at practically a constant level.

Further objects residing more especially in the details of construction, arrangement, 30 and operation of the mechanism, will be apparent from the following description in which reference is made to the accompanying drawings, forming a part of this specification, and wherein—

35 Figure 1 is a plan view of the rear portion of a paper feeding machine, illustrating my present improvement. Fig. 2 is a side elevation thereof. Fig. 3 is an enlarged side elevation of that part of the feeding machine adjacent to the feed table and looking at the relatively opposite side thereof as compared with Fig. 2. Fig. 4 is a detail longitudinal section taken therethrough substantially on line 4—4 of Fig. 1. Fig. 5 is a vertical cross section, enlarged, taken substantially on line 5—5 of Fig. 1. Fig. 6 is a detail perspective view of certain of the parts plainly shown in Fig. 3. Fig. 7 is a detail vertical section taken substantially on line 7—7 of Fig. 3. Fig. 8 is a perspective view looking from the base, of a portion of the feed table seen in Fig. 5. Fig. 9 is an enlarged detail section

of certain of the parts shown in Fig. 5, and to be more specifically referred to herein- 55 after. Fig. 10 is a detail vertical section through one of the paper stack engaging members. Fig. 11 is a similar view of another paper engaging member. Fig. 12 is a diagrammatic view illustrating the electrical connection for controlling the vertical adjustment of the feed table, and for use especially in connection with rough and uneven paper. Fig. 13 is a detail vertical section through certain parts of the apparatus shown in Fig. 12, and taken substantially on line 12—12 of said figure, and Fig. 14 is an end view of the paper stack shown in Fig. 12.

Referring now to Figs. 1 and 2 it will be 70 seen that at the rear of the feeding machine as shown, is arranged a frame in which the feed table is vertically adjustably disposed, this frame consisting of a base 50 from which a pair of standards 51 75 rise at each side, the upper ends of these standards supporting upper side frames 52 rigidly connected and spaced apart by the transverse tie rods 53 and 54 as best seen in Figs. 4 and 5.

By referring to Fig. 5 it will be noted that the upper side frames 52 have journals for the upper ends 55 of screw bars 56 disposed between the standards 51 at each side of the feed table frame, the upper extremities of which screw bars are provided with fixed bevel gears 57 in mesh with similarly 80 fixed bevel gears 58 of a transverse shaft 59 journaled at its end through the upper portions of the upper side frames 52, it being 90 also seen in Fig. 5 that one projecting end of the shaft 59 at the right hand side of the machine and looking forward, as will be seen by reference to Fig. 1, is provided with a ratchet wheel 60 rigidly secured thereto, 95 and having at one side a clutch face 61 with which the clutch socket 62 of a crank 63 is engageable, the crank itself being longitudinally adjustable upon one extremity of the shaft 59 to engage with and disengage 100 from the clutch face 61 just mentioned. At each side of the feed table frame thus formed, is arranged a longitudinally extending bracket 64, having end yokes 65, see Fig. 2, engageable with the standards 51 105 in sliding relation, and having a central

threaded bearing 66 through which the respective screw bars 56 extend, whereby upon rotation of the feed bars 56, the supporting brackets 64 will be raised and lowered, dependent upon the direction of such rotation. It will be noted that each of the supporting brackets 64 has upwardly projecting studs 67, one of which is plainly seen in Fig. 5, which are adapted to be received in conformable recesses in the lower surfaces of side cleats 68 secured to the under side of the feed table 69, whereby the latter may be disposed in proper relation with respect to the supporting brackets 64 by registering the recesses of its cleats 68 with the studs 67 just before mentioned.

By referring to Figs. 1, 5 and 8 it will be seen that the feed table 69 is provided at one side with inwardly projecting transversely extending slots 70 in which plates 71, seen in Fig. 8, are disposed, each of these plates 71 being provided with a clamping block 72 by which the same may be secured in selected adjustment within the slots 70 by a clamping bolt 73 seen in Fig. 5, each of said adjusting plates 71 also carrying a depending socket 74 adapted to receive the lower end of one of the upright paper guide rods 75, of which there are two at one side 30 of the paper stack 76, this stack being guided at its opposite side by means of a guide plate 77 as seen in Figs. 1 and 4, supported at the lower end of an arm 78, the upper end of which is adjustably connected by a wing nut 79 to a clamp 80, rigidly attachable to the tie rod 54 as plainly seen in Fig. 4. The plates 71 may be connected by a bar 71^a. Being thus located in proper position between the guide rods 75 and the 40 guide plate 77, the paper stack is moved forwardly against the upper end of spaced rigid upright guide strips 81 as plainly seen by reference to Fig. 4, this position shown in Fig. 1, being the normal position of the 45 stack ready for operation, although it is to be understood that the rods 75 and the guide plate 77 are laterally adjustable with respect to the feed table in order to accommodate a desired width of paper. With the 50 paper stack thus disposed in proper position, and elevated through the use of the hand crank 63 of the controlling shaft 59, the sheets are removed one at a time and fed forwardly by the action of a suction cylinder 82 journaled transversely above the forward edge of the feed table and immediately above the upper end of the forward spaced upright paper guide strips 81 before mentioned the relative arrangement of this 55 suction cylinder 82 being readily seen by reference to Figs. 1, 2, and 4.

In order to effect automatic vertical adjustment of the feed table 69, the controlling shaft 59 is provided upon its projecting end 65 with a loosely disposed weighted arm 83,

best seen in Fig. 3, and the weight of which tends to normally force the same downwardly and rearwardly, this weighted arm being provided with pivoted spring controlled pawls 84 at points diametrically opposed to one another with respect to the ratchet wheel 60, the sides of which they engage. The lower end of the weighted arm 83 is provided with a pivoted contact finger 85 which, by reference to Fig. 6, will be seen to have a slight rearward movement under control of a spring 86, and to be prevented from forward movement by a stop pin 87. This contact finger 85 normally engages the teeth of a curved rack 88 at the forward 80 portion of a horizontally extending latch 89, the rear end of which is pivotally mounted at 90 upon a stud 91 projecting from the adjacent upper side frame 52, and having a rearwardly projecting balancing arm 92 extending rearwardly beyond its pivot 90 and provided with an adjustable weight 93, as shown in Fig. 3.

At an intermediate point 94 of the latch 89 is pivotally connected the rear end of an arm 95 rigidly connected at its forward end to one end of a cross rod 96 which, as plainly seen in Fig. 1, is journaled transversely between the forward portions of the upper side frame and is provided intermediate its 95 ends with a controlling rod adjustably clamped thereto by a clamp 98, the said controlling rod 97 extending rearwardly above the paper stack 76 and carrying an adjustable element 99 which engages the top of the 100 paper stack itself. This paper engaging element 99 may either have a lower paper engaging roller 100 as seen by reference to Figs. 3 and 10, or may carry a depending rigid paper engaging pin 101 as shown in 105 connection with the element 102 as seen in Fig. 11, the element 99 in Fig. 10 being utilized with thick paper and the element 102 shown in Fig. 11, being used with thin paper. Thus during the use of the machine, as successive layers of the paper are fed from the top of the stack 76 by the action of the suction cylinder 82, the lowering movement of the paper engaging element 99 permits the rear end of the controlling rod 110 97 to lower, thus rocking the cross rod 96 and swinging the rear end of its arm 95 downwardly, the result of which is to slightly lower the forward end of the latch 89 upon its rear pivot 90, to permit swinging movement of the weighted arm 83 before mentioned, and as shown in dotted lines in Fig. 3, during which movement the pawls 84 slide over the teeth of the ratchet wheel 60. The lower portion of the weighted arm 83 however is provided with a laterally and outwardly projecting pin 103 disposed in a longitudinal slot 104 at the rear end of a connecting rod 105, the forward end of which is connected to the wrist pin 106 of 125 130

a crank 107, the latter being connected to one end of the suction cylinder 82 in a manner to be hereinafter described.

The slot 104 is of substantially the length 5 of its curved and inclined rack 88 of the latch 89 and, during constant rotation of the suction cylinder 82, the connecting rod 105 is continuously reciprocated so that whenever the weighted arm 83 is permitted swing- 10 ing movement, during which the pawls 84 slide over the ratchet wheel teeth as before described, the action of the connecting rod 105 immediately returns the weighted arm 83 to its normal position shown in full lines 15 in Fig. 3 and thus restores the automatic controlling parts to their original position. During the return movement of the weighted arm 83, the engagement of the pawls 84 with the teeth of the ratchet wheel 60 cause 20 a slight rotation of this ratchet wheel, and a similar rotative movement of the controlling shaft 59, which movement is communicated through the bevel gears 58 and 57 to the screw bars 56, rotation of which ele- 25 vates the feed table 69 through the side brackets 64 connected as before described.

By referring to Figs. 5 and 9, it will be noted that the shaft 59 before referred to, is provided adjacent one end and between 30 the upper side frames 52, with a loose pulley 108 having an annular flange 109 provided in its outer face with an aperture 110, this aperture being adapted for the reception of a clutch pin 111 carried by an annular clutch plate 112 securely fastened to the shaft 59 at 113. This clutch pin 111 is normally held in inoperative withdrawn position as shown in Fig. 5 during the operation 35 of the machine. When the stack of sheets 40 76 is exhausted, or nearly so, however, the clutch pin 111 may be thrown in, thus coupling the loose pulley 108 to the shaft 59, the operator at the same time withdrawing the pawls 84 from the ratchet wheel 60. 45 Around the pulley 108 is extended the rear end of a belt 114, the forward end of which belt as plainly seen in Fig. 1, is extended around one end portion of the suction cylinder 82 (see also Fig. 6) so that, when the 50 pulley 108 is clutched, the rotation of the suction cylinder 82 is communicated to the shaft 59, rotating the same to similarly rotate the screw bars 56 and the lower table 69.

From Fig. 5 and also from Fig. 2, it will be noted that one of the bearings 66 of the adjacent side bracket 64, is provided with an extended bearing or tubular piece 115 loosely through which extends a vertical rod 116 having an adjustable set collar 117 secured thereon below the said side bracket, and with which the extended portion 115 just mentioned comes into engagement as shown in dotted lines in Fig. 5, when the table is lowered through the action of the belt 114, thus causing lowering movement

of the rod 116, the upper end of which is secured to a flexible connection 118 passing over a pulley 119 supported upon the adjacent upper side frame 52 and connected at its forward end to a clutch operating member for disengaging a clutch in the driving connections to the suction cylinder 82 as hereinafter described, when the table 69 has been thus lowered.

The automatic means before described for 75 elevating the table 69 in step by step movement during the usual operation of this machine, are well adapted to serve the intended functions in connection with either rough or smooth paper which is even and regular. 80 Where uneven or irregular paper is encountered, however, I preferably use a modified form of actuating mechanism shown in Figs. 12, 13, and 14.

Referring now to Fig. 12, which is more 85 or less diagrammatic in form, I have shown the contact pin 85^a of the weighted arm 83^a which carries the pawls 84^a in engagement with the ratchet wheel 60^a, as normally held by the shouldered end 120 of a lever 121 intermediately fulcrumed at 122 and having a rearwardly projecting arm 123 provided with an adjustable weight 124 counterbalancing the same, the end 120 of this lever constituting an armature and being disposed 90 adjacent to electromagnets 125. A battery 126 is in circuit with the electro-magnets 125 through circuit wires 127 and 128, the latter of which includes a mechanical switch 129. The circuit wires 100 127 and 128 respectively lead to a rigid arm 130 and one end 131 of an intermediately pivoted lever 132, the opposite end of which lever is provided with a vertically adjustable paper engaging element 133 normally 105 disposed upon the rear central portion of the paper stack 76^a as shown in both Figs. 12 and 14, the said rigid arm 130 and the said end 131 of the lever 132 being provided with registering contact pins 134 and 135 respectively, which upon lowering movement of the rear end of the lever 132, come into engagement and complete the circuit through the electro-magnets 125 which attract the armature 120 and thus release the contact 110 piece 85^a of the weighted arm 83^a which is thus free to move downwardly and rearwardly by gravity and is returned in order to raise the paper holding table by connections 105^a corresponding to the connections 120 105 previously described. There is also shown in Fig. 12 a pair of rods 53^a and 54^a, and a shaft 59^a corresponding to the tie rods 53 and 54 and the shaft 59 of the figures

before described, it being noted that in the 125 automatic mechanism illustrated in Fig. 3, a frame 136 is clamped by a clamp 137 to the rod 53^a, this frame having a lower horizontally slotted portion 138 adjustably carrying an insulated support 139 above the 130

paper stack 76^a, by means of a clamp 140, this insulated support 139 carrying the rigid arm 130 and the lever 132 before mentioned, which connections together with the clamp 5 140 will be better seen by reference to Fig. 18. There is also shown in Fig. 12 a cross rod 96^a corresponding to the cross rod 96 in the figures before mentioned, to which rod 96^a are loosely connected the forward ends 10 of rearwardly projecting rods 141 disposed upon opposite sides of the lever 132 and having adjustable paper engaging members 142 adjacent their rear ends, the function of which is to press downwardly upon the 15 paper stack 76^a due to the weight of the rods 141 and assist in maintaining the rough uneven stack 76^a as flat as possible.

Referring again to Fig. 2 it will be noted that the reduced end portion of the suction cylinder 82 is provided with a pair of gears 168 and 169 in respective connection with separate gears 170 and 171 of the shaft 172 of a wooden roller 167. Power is applied to the shaft 172 of the wooden roller 167 25 through a sprocket chain 190 to its sprocket wheel 191, this sprocket wheel 191 being connected to the shaft 172 of the wooden roller 167 by means of a clutch at 193, having an operating member 194 to which the flexible 30 connection 118 before mentioned, is connected so as to disengage the clutch 193 when the table has been lowered so that the extension 115 strikes and lowers the set collar 117 of rod 116.

35 I claim:—

1. In a paper sheet feeding machine, a 40 vertically adjustable feed table on which the paper is supported, means for automatically raising the feed table in step by step movement during operation, including a transverse rotatable shaft, a pulley loosely 45 mounted on said shaft, a clutch for connecting the said pulley with the said shaft, driving connections leading to said pulley for lowering the said feed table and including a clutch, and means for automatically releasing the said clutch of the driving connections when the table has been lowered to a predetermined point.

50 2. In a paper sheet feeding machine, a 55 vertically adjustable feed table on which the paper is supported, side brackets upon which the said feed table is disposed, having threaded bearings, vertically extending screw rods projecting through the said bearings, a transverse shaft having geared connection with the upper ends of said screw bars, means for automatically rotating the said shaft to raise the feed table in step by 60 step movements during the operation of the machine, and as paper is fed therefrom, a pulley loosely mounted upon the said shaft, a manual clutch for connecting the pulley with the shaft, driving connections leading 65 to the said pulley for lowering the said feed

table, said driving connections including a clutch, and means for automatically releasing the said clutch of the driving connections when the table has been lowered to a predetermined point.

3. In a paper sheet feeding machine, a 70 vertically adjustable feed table on which the paper is supported, supports for the said feed table including vertically extending screw bars, side brackets through which the 75 said screw bars project and upon which the feed table is disposed, a shaft having geared connection with the said screw bars, means for automatically rotating the said shaft whereby to raise the feed table in step by 80 step movements during the feeding operation, a pulley loosely mounted upon the said shaft, a manual clutch for the said pulley, driving connections for the said pulley including a clutch, means for releasing 85 the said clutch of the driving members when the table has been lowered to a predetermined point, said means including an apertured projection carried by one of the 90 said supporting brackets of the feed table, and a vertically movable rod extending through the said apertured projection, said rod having a flexible connection at its upper end with the said clutch of the driving connections, and having an adjustable set collar thereon below the said apertured projection, for the purpose described.

4. In a paper sheet feeding machine, a 100 vertically adjustable feed table on which the paper is supported, a support for the said feed table including vertically disposed screw bars and side brackets through which the 105 said screw bars are threaded and upon which the feed table is disposed, a shaft having geared connections with the upper ends of the said screw bars, a ratchet wheel carried by the shaft, a weighted arm revoluble on the shaft and provided with pawls in engagement with the said ratchet wheel, and also provided with depending 110 contact piece, a vertically movable latch member having an inclined rack with which the said contact piece engages to normally prevent movement of the weighted arm, driving connections for returning the said 115 weighted arm to normal position after movement thereof, and connections for lowering the said latch member, said connections including an element disposed upon, and in engagement with, the paper stack 120 upon the feed table.

5. In a paper sheet feeding machine, a 125 vertically adjustable feed table, screw bars on which the said table is supported, means for rotating the said screw bars to elevate the feed table, an intermediately pivoted latch member normally preventing rotation of the said screw bars and having an adjustable weight adjacent one end, and means for releasing the said latch member includ- 130

ing an arm extending above the paper stack upon the feed table, and a paper engaging element adjustably secured upon the said arm and adapted to rest upon the paper

5 itself.

6. In a paper sheet feeding machine, a vertically adjustable feed table on which the paper is supported, screw bars on which the said table is adjustably mounted, a shaft

10 having geared connection with the said screw bar, a ratchet wheel carried by the said shaft, a weighted arm revoluble on the shaft and having pawls in engagement with the said ratchet wheel, said arm being pro-

15 vided with a depending contact piece and with a laterally projecting pin, driving connections for returning the weighted arm to normal position after each movement there-

of, and including a slotted connecting rod,

20 the slot of which receives the said laterally projecting pin of the said arm, a latch member pivoted at one end and provided at its opposite end with an inclined rack engaging

25 the depending contact piece of the weighted arm, and connections for lowering the said latch member as sheets are fed from the stack, said means including an oscillatory

30 shaft having a rigid arm, one end of which is attached to the latch member, and a second arm adjustably connected to the said shaft and extending above the paper stack, together with a member adjustably secured upon the last mentioned arm and resting upon the paper stack itself.

7. In a paper sheet feeding machine, a 35 vertically adjustable feed table, screw bars on which the said table is adjustably supported, means for rotating the said screw bars to elevate the table during the feeding operation, comprising a ratchet mechanism 40 having a weighted pawl carrying arm, a pivoted latch member having a stepped pawl engaging face and normally preventing movement of the said pawl carrying arm, and means for automatically withdrawing the said latch member including an oscillatory shaft, a connecting arm leading from said shaft and pivotally connected to said latch member intermediate the ends of the latter, and a controlling member ad- 45 justably mounted and resting directly upon the paper carried by the feed table, all sub- 50 substantially as described.

8. In a paper sheet feeding machine having driving means including a clutch, a vertically adjustable feed table, clutch controlled connections with the driving means for lowering said feed table, and adjustable means for automatically releasing the clutch of the driving means when the feed table has 55 been lowered to a predetermined position, including a member disposed vertically along one side of the said feed table and having connection with the said clutch, and an adjustable stop on the said member with which 60 the table is engageable.

ALBERT BROADMEYER.
